PRESSER-FOOT MECHANISM.

1,177,249.

Specification of Letters Patent. Patented Mar. 28, 1916.

Application filed April 24, 1915. Serial No. 24,135.

To all whom it may concern:

Be it known that we, LAWRENCE E. JOHNSON, a citizen of the United States of America, and a resident of Winthrop, in the county of Suffolk and State of Massachusetts, and EDWARD ERICKSON, a subject of the King of Sweden, and a resident of Lynn, in the county of Essex and State of Massachusetts, have invented certain new and useful Improvements in Presser-Foot Mechanisms, of which the following is a specification.

This invention relates to improvements in presser foot mechanisms for shoe sewing machines having for its object the production of a device which will automatically accommodate itself to various thicknesses of material and in so doing will regulate the length of thread to be drawn from the source of supply.

The present invention is an improvement on U. S. Letters Patent No. 1,133,149, issued March 28, 1915, and to which reference may be made for the operation of certain parts of the machine which are not herein shown, as they form no part of the invention herein claimed.

The invention consists in certain novel features of construction and arrangement of parts which will be fully understood by reference to the description of the drawings and to the claims hereinafter given.

Of the drawings: Figure 1 represents a vertical section of a sewing machine, showing a presser foot mechanism and thread measuring device controlled thereby, said mechanisms embodying the principles of the present invention, and Fig. 2 represents a horizontal section of a portion thereof, the cutting plane being on line 2-2 on Fig. 1.

Similar characters designate like parts throughout the figures of the drawings.

In the drawings, 20 is the base of the machine adapted to be secured to a column and having the end frames 21 provided with bearings for the revoluble shaft 23. The revoluble shaft 23 is rotated by a driving wheel secured to one end thereof. Interposed between the side frames 21 and keyed to the shaft 23 is the cam disk 27. To the inner side of one of the side frames 21 is secured the work support 28 which may be of any well-known construction.

The thread *t* is drawn from any suitable

source of supply and passes over a fixed rod 55 103 extending from one side frame 21 to the other, a pin 104 extending outwardly from this rod 103 positioning the thread *t* thereon and preventing it from slipping lengthwise thereof during the feeding of the work. The 60 movement of the work in feeding is toward the left and the pin 104 is placed at the left of the thread to prevent slipping in that direction. The thread *t* then passes around a pin 105 secured to the thread lock cam 65 lever 106 which is pivoted at 107 and has at its rear end a roller 108 in the cam path 109 formed in the right hand side of the disk 27.

The thread *t* passes from the pin 105 70 over a stationary pin 110 in the side frame 21 and then through slots in two downwardly extending arms 111 of a forked member 112. The thread *t* passes from one arm 111 to the other arm 111 under a stud 75 or pin 113 projecting horizontally from the side of the forward end of the lever 106. From the forked member 112 the thread *t* passes through a hole 114 in the movable frame 62 to an eye on one of the side frames 80 21 and thence into the wax pot 116 secured to the side frames 21 in any well-known manner. To the front wall of the wax pot 116 is clamped, by means of the clamp screw 118, a support 119 provided with a 85 sheave 121 around which the thread *t* passes through the liquid wax in said pot 116.

The disk 27 is provided on its right hand face with a cam path 141 in which is positioned a roller 142 mounted on the end of 90 the lever 143 pivoted at 144 and provided at its outer end with a pivoted block 145 between which and a guide wall 145^x is mounted the slidible member 112 having rack teeth 146 in one edge thereof.

The pivot 144 is provided with a gear 147 on its inner end the teeth of which mesh with the rack teeth 146 of the member 112. A plate 148 secured to the end of the lever 143 prevents the displacement of the member 112. This rack member 112 is provided with a lateral extension 149 to which is secured the presser foot 150 of ordinary construction. The extension 149 forms a head to the slidible member 112 which is adapted to contact with the upper face of the lever 143 to limit the downward movement of said member 112.

Extending upwardly from the extension 149 and through the member 151 secured to the lever 143 is a rod 152 surrounded by a helical spring 153 which tends to retain the 5 presser foot 150 in its normal position and against the tension of which said presser foot is adapted to be lifted.

The pivot member 144 is mounted in a tubular sleeve 154 revolvable in the frame 10 22 but prevented from end movement by the pin 155 extending into the annular peripheral groove 156 therein. The reduced end 157 of the sleeve 154 extends into the lever 143, this end 157 of the sleeve 154 and 15 a portion of the shank 144 forming the pivot for said lever. The lower end of the presser foot 150 has an operating face 158 parallel with the upper face of the work support 28.

It is obvious that when the slidable member 112 is moved transversely of the outer 20 end of the lever 143 the lower face 158 of the presser foot 150 and the upper face of the work support 28 will remain constantly in parallelism in whatever position the 25 presser foot may be while exerting a gripping pressure upon the work.

Secured to the shank 144 is an arm 159 adapted to be manually operated to adjust the presser foot 150 relative to the lever 143 30 and to accommodate it to varying thicknesses of material. This is accomplished by the operator moving the arm 159 and thereby turning the pinion 147, raising and lowering the presser foot at will.

When any work is placed upon the support 28 the operator adjusts the presser foot 35 in the manner just described so that it will rest upon the upper face of the work, after which it will be automatically adjusted as 40 the material varies in thickness.

Opposite the end of the shank 144 and the outer face of the lever 159 secured thereto, is a friction member 160* consisting of a pad 161 in a recess in the inner face of the ear 45 162 on the lever 163, this pad 161 having a shank extending through and threaded to said ear 162 which shank is provided with a locknut 164 to retain said pad in adjusted position.

The lever 163 is pivoted to the frame 22 50 and has at its rear end a roller 166 held in contact with a cam in the right hand face of the disk 27 by means of a spring, as fully shown and described in said Patent 55 1,133,149, hereinbefore referred to.

When the presser foot is moved downwardly by the cam controlled lever 143 the work will be securely gripped thereby against the support 28, the face 158 being 60 forced into the face of the work by the cam 141. The machines are built with a loose fit for the rod 152 in the member 151 to permit of the member 112 being cramped between the guide wall 145* and the opposed 65 face of the pivoted block 145 when the lever

143 is moved about its pivot 144. Just prior to the roll 142 entering the throw 160 to release the gripping pressure upon the work the pad 161 is moved into contact with the outer face of the lever 159 and locks the 70 pinion 147, thereby preventing any sliding movement of the member 112. Consequently, when the roller 142 enters the throw 160 the presser foot 150 will be bodily lifted from the work and will remain free from 75 contact therewith until the completion of the feeding operation, when it will be released and the spring 153 will be permitted to return the presser foot into light contact with the work before the roll 142 enters the 80 concentric portion of the cam 141 to produce the gripping pressure upon the work.

Owing to the fact that the slidable member 112 is located outside of the pinion 147 and between it and the face of the block 145 pivoted to the lever 143, any movement imparted to said lever 143 by the cam path 141 will be imparted to the presser foot 150, thereby removing it from the work when it is desired to feed the latter, or exerting 90 a gripping pressure when the work has been fed. The main portion of the cam path 141 retains the operating face 158 of the presser foot 150 in contact with the work on the support 28 and causes it to exert a gripping 95 pressure thereon, but when it is desired to move the work along the support, the roller 142 of the lever 143 moves into the portion 160 of the cam path 141, thereby causing the presser foot to be lifted from the work temporarily while said work is being moved upon the support into a new position.

The pin 113 is adapted to move in the forked end of the member 112, said pin being moved by the action of the cam path 109 105 on the lever 106 in the end of which said pin is mounted. The cam path 109 is provided with a throw adapted to oscillate the lever 106 at the proper time to measure off the given quantity of thread for the 110 stitch, the pin in doing this moving longitudinally of the slot in the end of the member 112. As the thread *t* in crossing this slot passes beneath the pin 113 it is obvious 115 that if the slidable member 112 was always in the same position a given length of thread would always be measured by the oscillation of the lever 106 and the movement of the pin 113. It is desired, however, to measure off different lengths of thread 120 for different thicknesses of material and this is readily accomplished by means of the slidable member 112, it being self-evident that when the presser foot 150 is raised the thread carrying passages in the arms 111 125 of the member 112 are similarly raised to a new position corresponding with the thickness of the material and when in this raised position a greater quantity of thread 130 will be drawn from the source of supply.

by the movement of the pin 113 in the forked end of the member 112, the lowermost position of said pin being the same under all conditions. It is obvious that this 5 thread measuring device will operate after the presser foot 150 has returned into contact with the work. When the takeup device is operating, the pin 113 will be in its highest position and the pin 105 will be in position to coact with the pin 110 to lock 10 the thread to prevent it from being fed from the source of supply.

The roller 108 is of less diameter than the width of the cam path 109 and is in 15 contact with the inner wall of said path only when the lever 106 is being moved about its pivot to measure the thread. The roller 108 never contacts with the opposite wall of said path. The pivot member 107 20 has secured to its outer end an arm to the end of which is secured a spring the opposite end of which is fastened to the frame 21, all as shown and described in the patent referred to. This spring retains 25 the pin 105 in contact with the pin 110 except during the thread measuring operation.

As described in the aforesaid patent, the pivot member 107 is revolvably mounted in 30 an eccentric bushing in the frame 21 to which it is clamped by a bolt when adjusted by the handle. By adjusting the position of the pivot member 107 in this manner the normal length of thread for each stitch may 35 be regulated, while by means of the mechanism for positioning the slide 112 the supply of thread for various thicknesses of material may be automatically determined, the various lengths of thread measured off being 40 proportionate to the thicknesses of material through which the thread is to be fed.

After the hook of the shuttle has carried the loop of thread to a point where it should be dropped to encircle and be drawn 45 up with its companion thread to form a stitch, the takeup lever is operated to put the proper stress upon the needle thread to effect this result. It is then necessary to lock this thread between the takeup and the 50 thread supply (not shown) to prevent it from being drawn from the latter. This is accomplished by the locking pins 105 and 110, the cam path 109 being so constructed as to effect this result at the proper time. 55 It will be seen that with this locking device 105-110 the thread is positively held against movement without danger of the takeup "stealing thread" from the supply and failing to properly set the stitch.

60 The machine is provided with mechanisms for forming the stitch, feeding the work, forming the loop, all as fully described in Letters Patent of the United States No. 1,133,147 issued March 23, 1915, 65 on which this application is an improve-

ment. As these mechanisms form no part of the present invention no detailed description thereof is herein given.

The pivot for the block 145 consists of a cylindrical stud 200 having a reduced end 70 201 threaded to the lever 143 as shown in Fig. 2 of the drawings.

The plate 148 is secured to the lever 143 by means of the screws 202 and a screw 203 extending therethrough and threaded to the 75 outer end of the stud 200 as shown in Fig. 2.

The provision of the pivoted block 145 is of great importance for it has been found in practice that while a construction in which the slide 112 reciprocates between two parallel fixed walls works satisfactorily when new and when oil has not spread over its contacting surfaces, it does not work well when the parts have become worn or thoroughly lubricated and the cramping 80 85 effect desired between the lever 143 and slide 112 will not be assured at all times.

It is quite essential that some provision be made so that the sliding member 112 will be positively locked to the lever 143 when 90 the presser foot 150 is in gripping contact with the work and it has been found in practice that this result will be attained by the use of the pivoted block 145.

It is obvious that when, in the rotation of 95 the cam disk 27 in the direction of the arrow *a*, the roller 142 moves from the cam throw 160 to the concentric portion of the cam path 141, the face 158 comes into contact with the work and tends to lift the presser foot 150 which in turn will tend to cant the sliding member 112 in the transverse groove in the lever 143 formed by the guide wall 145* and the opposed face of the block 145. When this canting of the slide 112 occurs 100 105 the block 145 will be moved about its pivot 200 causing the upper end thereof to move inwardly toward the fixed guide wall 145* and thereby forcing the sliding member 112 into such firm contact therewith that any 110 sliding movement of the member 112 is effectively prevented until this pressure is removed. This removal of the locking pressure on the sliding member 112 will not take place until the roll 142 again moves into the 115 cam throw 160.

When the block 145 becomes worn so as to be inoperative it may be replaced with a new block without discarding the entire lever 143 which was necessary when the 120 guide walls 145* of the lever 143 were both formed integral therewith.

It is obvious that by the construction herein shown and described a very effectual presser foot mechanism is provided that is capable of regulating the amount of thread to be drawn from the source of supply, this amount depending upon the thickness of the material being operated upon.

It is believed that the operation of the 125 130

mechanism and its many advantages will be fully apparent without further description.

Having thus described our invention, we claim:

1. The combination of a pivoted lever provided with a guide wall; a block pivotally mounted on said lever with a face thereof opposed to said guide wall; a member slidably mounted between said wall and block and adapted to be moved with said lever about its pivot; and a presser foot secured to said slidable member.

2. The combination of a pivoted cam-controlled lever; a slidable member carried

thereby and movable transversely thereof at a point intermediate the pivot and outer end; a presser foot on said slidable member; a work support; means for moving said slidable member endwise; a pivot pin in the outer end of said lever parallel to its axis; and a block mounted thereon with a face thereof abutting the outer side face of said slidable member.

Signed by us at 4 Post Office Sq., Boston, Mass., this 22nd day of April, 1915.

LAWRENCE E. JOHNSON.
EDWARD ERICKSON.
